PROCESS OF REFINING ASPHALT BASE
PETROLEUMWalter S. Baylis, Los Angeles, Calif., assignor to
Filtrol Company of California, Los Angeles,
Calif., a corporation of California

Application February 17, 1930, Serial No. 428,993

3 Claims. (Cl. 196—79)

This invention relates to the art of preparing light-colored distillates of asphalt base petroleum. It is particularly concerned with the production of pale, high grade lubricating cuts from such 5 oils.

In my co-pending application Serial No. 232,739, filed November 12, 1927, I disclosed how oil of the Pennsylvania type, which has a paraffin, not an asphalt base, might be treated to distill 10 light oils and decolorize simultaneously lubricating cuts. The present application is a continuation in part of the above named one and it contemplates the removal of tarry and asphaltic substances from crude petroleum, which is then 15 treated in substantially the same manner as disclosed in the earlier-filed case.

Among the objects of the present invention are: the efficient application of an adsorbent to petroleum; the rapid handling of petroleum; 20 and its separation into the desired cuts with the minimum of time and apparatus.

A very important object is to render it possible to produce lubricating oils of the lightest color and best lubricating qualities from crudes heretofore not regarded as being especially suitable for 25 the purpose.

Further objects and advantages will be made manifest in the following description and in the accompanying drawing in which an apparatus 30 suitable for carrying out the method of my invention is diagrammatically illustrated. It is to be understood that other apparatus may be employed.

In the drawing, which is a side elevation, partly 35 in section, 1 represents a conical bottom tank provided with an agitator 2. In a bottom discharge pipe 3 there is a valve 4. The tank 1 is also provided with a filling pipe 5 for crude oil, having therein a valve 6, and a pipe 7 for concentrated sulfuric acid, having therein a valve 8. The discharge pipe 3 connects with a filling pipe 36 of 40 a second agitating tank 12. To the pipe 36 there is connected a sludge discharge pipe 9 having therein a valve 10. In the pipe 36 near the point 45 where the pipe 9 connects with the latter, there is a valve 11 which is located nearer the tank 12 in the pipe 36 than the point where the pipe 9 joins the latter.

The second agitating tank, denoted by 12, is a 50 substantial duplicate of the first except that it is provided with an inlet pipe 37 for powdered adsorbent. In this pipe is a valve 37a. In the tank 12, 38 is an agitator, 39 the gears for driving the latter, 36 the inlet pipe from the tank 1, and 40 55 the outlet pipe from the tank 12. In the pipe

40 there is a valve 40a. The pipe 40 connects with the suction end of a pump 13.

Connecting the discharge end of the pump 13 with the intake end of the series of heat exchangers 14 is a pipe 41. Connecting the outlet 5 end of the series of heat exchangers 14 with the intake end of the pipe still 15 is a pipe 45. The pipe still 15 is heated in any suitable manner as by fuel supplied by a burner 46. A steam pipe 42 having a valve 43 is provided at an elbow of 10 the pipe 45 so that steam may be introduced into the oil entering the pipe still. The discharge end of the still 15 is connected to an intermediate portion of the atmospheric column 16 by a pipe 48. Beneath the point at which the pipe 48 15 enters the column 16, a series of baffle plates 49 and 50 is disposed in alternating relation so that any liquid discharged through the pipe 48 into the column 16 must pass in a circuitous route 20 from the point of discharge to the bottom of the column 16.

Disposed in the atmospheric column 16 above the point at which the pipe 48 connects thereto are pairs 55 of baffle plates 49 and 50. These pairs 55 are positioned in spaced relation so as 25 to make room between adjacent pairs for collector pans 56. Each of the collector pans 56 is connected by a pipe 57 to one of the heat exchangers 14 from which pipes 58 lead to suitable 30 distillate storage tanks. Leading from the upper end of the atmospheric column 16 is a gasoline vapor line 60. Connecting the lower end of the atmospheric column 16 to the inlet end of the cooler 17 is a pipe 61. Connecting the discharge end of the cooler 17 to the inlet end of the pump 35 18 is a pipe 62 into which a solvent pipe 63 connects. The discharge end of the pump 18 is connected to the filter press 19 by a pipe 64. The filter press 19 may be any suitable type of press, but it is preferably a Sweetland press. Leading 40 from this press is a liquid discharge pipe 65.

The operation of the apparatus above described in carrying out the process of my invention is as follows:

The process is designed to be continuous, except as to the operation of the first agitating tank or tanks (No. 1). In order to make the operations following those carried out in the tank 1 continuous, I prefer to use a battery of acid treating tanks similar to tank 1.

A suitable charge of crude oil is first run into the tank 1 through the pipe 5, the agitator started, and a charge of concentrated sulfuric acid is run in from the pipe 7. The amount and concentration of the acid will vary with the kind of 55

crude oil worked upon as well as with the time of treatment given. It is therefore impossible to give exact directions as to these factors. The art of asphalt removal from crude by sulfuric acid is quite well understood, however, in the oil refining industry, so persons skilled in the art will well know how to perform the step. Asphalt and tar removal should be approximately complete.

- 10 After a suitable period of agitation and settling, the valve 11 is closed and the valves 10 and 4 are opened to allow the acid sludge to flow to waste through the pipes 3 and 9. As soon as oil begins to flow, the valve 10 is closed and the valve 11 is opened. By manual operating of a battery of tanks similar to the tank 1 a supply of acid-purified, asphalt-free petroleum is intended to be fed continuously into the agitating tank 12. Nothing beyond ordinary skill is necessary to so manipulate a battery of acid treating tanks. Air agitation instead of mechanical agitation may be used in them, and in fact, any standard method of acid treatment may be used in place of the above described process. The oil 25 is not neutralized before further treatment.

At the same time that a stream of purified oil is being fed into the agitating tank 12, a continuous supply of a suitable adsorptive agent, which is preferably the acid-treated clay known to the trade as "Filtrol" but which may be any of the other well known adsorptive clays, is fed into the agitator 12 through the pipe 37. "Filtrol" is an acid-activated clay made by a process somewhat similar to that disclosed in the United States Patent No. 1,397,113 to Paul W. Prutzman. The agitator 38 is rotated constantly so as to mix the petroleum and the adsorptive agent as these are fed into the agitating tank 12 through the pipe 40 by the pump 13, and discharged through the pipe 41 into the upper end of the series of heat exchangers 14. At this point the valve 43 may be opened and steam forced into the mixture so as to raise the temperature of the mixture and increase the adsorptive tendency which the adsorptive agent has on the petroleum as the temperature of the mixture is gradually raised in its passage through the series of heat exchangers 14.

The mixture usually enters the first of the heat exchangers 14 at a temperature of approximately 240° F. and leaves the last of the heat exchangers 14 through which it passes at a temperature of approximately 410° F. The mixture is then conducted through the pipe 45 to the pipe still 15, where it is raised to a temperature of substantially 750° F., at which temperature it is discharged from the pipe 48 into the atmospheric column 16.

The mixture entering the column 16 flows down through a circuitous path over the baffle plates 49 and 50 and releases all of the lighter fractions of the petroleum so that the residuum which collects in the lower end of the column 16 comprises a mixture of fractions which is termed "cylinder stock" and which has an average density of 26° Bé.

The various fractions of petroleum which pass upward through the column 16 in the form of vapors are condensed and cooled in the various pans 56, and flowing outward through the heat exchangers 14, effect a rise of the temperature of the petroleum and adsorptive-agent mixture as previously mentioned. Any gasoline vapor which 75 is not condensed in the upper of the pans 56 passes

from the column 16 through the gasoline vapor line 60 to a suitable condenser, not shown.

The various fractions thus condensed in the column 16, in order of decreasing boiling points, may include the following:

	Fahrenheit
Wax slop	B. P. 650°
Wax distillate	B. P. 600°
Gas oil	B. P. 550°
Mineral seal	B. P. 500°
Kerosene	B. P. 425°

The cylinder stock which collects in the lower end of the column 16 flows through the cooler 17 and the pipe 62 to the pump 18. At this time a suitable solvent is introduced through the pipe 63 into the cylinder stock so that it may be handled more easily by the pump 18 and filter 19. The pump 18 forces the diluted cylinder stock through the pipe 63 into the filter press 19 which 20 retains the adsorptive clay and permits the purified cylinder stock to be discharged through the pipe 65 which conducts it to a suitable place of storage. When a sufficient amount of cake has been formed in the filter press 19, the flow of mixture through this filter press is stopped and switched to another similar filter press held in readiness for this purpose. The cake in the filter press 19 is then washed with a suitable solvent so as to remove any of the remaining cylinder 30 stock from the cake. Suitable provision may also be made for blowing the cake in the press with either air or steam after removing the retained oil so as to drive out the excess of solvent and dry the cake. Thereafter the filter press is opened 35 and the cake removed and conveyed by any suitable means, such as a belt conveyor, to the extraction equipment where the oil can be recovered and then to the reactivating house where the clay is reactivated so as to again be suitable for use 40 in the above described process.

As stated above, this process has been particularly successful with the use of Filtrol, which is a product that has been chemically treated so that there are no elements therein to cause any chemical reaction when acid is added to it. Therefore, no sulphates are formed as is the case when acid is added to a natural or untreated earth.

When "Filtrol" is used as the adsorptive agent, it is possible to add a slight amount of acid in 50 the reactivating process so that the "Filtrol" acts as a carrier for the acid in an unaltered state. Thus, due to the enormous surfaces in the "Filtrol" on which the acid is carried in a thin film, there is very powerful action on the oil, even 55 when an extremely small amount of acid has been added to the "Filtrol".

Another great advantage of using the acid in this manner is that it acts upon the oil without being given up by the "Filtrol" so that neutralization of the final oil product is unnecessary.

It is also desired to point out that the impure substances are absorbed by the adsorptive clay before the vapors are discharged from the mixture of oil and clay in the column 16, so that 65 fractions condensed in the pans 56 of the column 16 are already purified and further treatment of these is therefore unnecessary.

A novel and very important feature of my invention is thus seen to be the treatment with an 70 adsorptive agent of the oil being distilled in both its liquid and vapor phases. Another novel feature of importance is treating these liquid and vapor phases as they are interchanging with each other by alternate vaporization and condensa- 75

tion. The purification of the various products into which the oil is divided is thus accomplished concurrently with the distillation and with an efficiency and purity of product hitherto unknown.

While I have described a continuous process I do not limit myself thereto since my invention can be operated as a batch process by anyone skilled in the art who is in possession of the information communicated herein.

It will be noted that my process depends for its efficiency upon the fact that certain adsorptive materials, of which Filtral is a good example, have a selective affinity for certain vaporizable impurities commonly found in petroleum distillates. If an oil containing these impurities is mixed with such a material, the impurities are adsorbed (or possibly absorbed) in the material and are held therein even if the mixture is subjected to temperatures at which the impurities are normally vaporizable. It is then possible by spreading the mixture in a film thin enough to eliminate any substantial static pressure on the vapors, to cause a substantial evolution of vapors free from said impurities.

I claim as my invention:

1. A process of treating crude oil having tar and asphalt content which consists in eliminating the tar and asphalt content by agitating such an oil with concentrated sulphuric acid and separating the oil from the sludge produced thereby, mixing decolorizing clay with the oil, passing the resultant mixture through a heating zone and heating the same to a temperature sufficient to vaporize lighter fractions of the crude oil, introducing the mixture to a fractionating zone at a point substantially above the bottom thereof whereby unvaporized portions of the mixture descend toward the bottom of said fractionating zone and released vapors ascend toward the top thereof, condensing heavier fractions of the released vapors in the portion of said fractionating zone above the point of introduction of the mixture thereto, separately withdrawing the condensed fractions from the fractionating zone, removing lighter fractions of the released vapors from the top of said fractionating zone and subjecting the same to condensation, withdrawing the mixture of unvaporized lubricating stock and clay from the bottom of said fractionating zone,

and separating the clay from said lubricating stock.

2. A process of refining hydrocarbon oil containing asphaltic substances for the production of lubricating stock therefrom which comprises agitating such an oil with concentrated sulphuric acid, separating the oil from the sludge produced thereby, mixing a clay adsorptive with said oil, passing the resultant mixture through a heating zone and heating the same to a temperature sufficient to vaporize lighter fractions of the crude oil, introducing the mixture to a fractionating zone at a point substantially above the bottom thereof whereby unvaporized portions of the mixture descend toward the bottom of said fractionating zone and released vapors ascend toward the top thereof, condensing fractions of the released vapors heavier than gasoline in the portion of said fractionating zone above the point of introduction of the heated mixture thereto, separately withdrawing the condensed fractions from the fractionating zone, removing gasoline vapors from the top of said fractionating zone and subjecting the same to condensation, withdrawing the mixture of unvaporized lubricating stock and clay from the bottom of said fractionating zone, and separating the clay from said lubricating stock.

3. A process of refining hydrocarbon oil containing asphaltic substances for the production of lubricating stock therefrom which comprises agitating such an oil with concentrated sulphuric acid, separating the oil from the sludge produced thereby, mixing a clay adsorptive with said oil, passing the resultant mixture through a heating zone and heating the same sufficiently to vaporize lighter fractions of the oil, introducing the mixture to a separating zone at a point substantially above the bottom thereof, passing the mixture downwardly toward the bottom of said separating zone in relatively thin layers to assist the release of vapors therefrom, condensing released vapors in the portion of said separating zone above the point of introduction of the mixture thereto, separately withdrawing condensed vapors from the separating zone, removing the mixture of unvaporized lubricating stock and clay from the lower portion of said separating zone, and separating the clay from said lubricating stock.

WALTER S. BAYLIS. 50
